UNITED STATES PATENT OFFICE

JOSEPH L. BARTH, OF BISMARCK, NORTH DAKOTA

METATARSAL-PAD LOCATOR

Application filed July 26, 1928. Serial No. 295,386.

This invention relates to an apparatus or device designed for use in diagnosing foot troubles particularly for determining the point of contact between any part of the foot and the in-sole of a shoe, to aid in properly placing a metatarsal pad into the shoe and also to aid in the cutting of holes in the in-sole of the shoe directly under corns or callouses for the purpose of providing a pocket or space therefor.

The present invention is generally of the nature disclosed in my Patent No. 1,684,339 for pedo-graph and metatarsal pad locator, issued September 11, 1928, and it constitutes an improvement thereover.

It is particularly aimed to provide a novel construction or mounting for the flexible arch-engaging member and to provide a novel means for inking and preventing drying of the ink transfer member, and further to provide a novel construction wherein a cam is used to both flex the arch member and maintain the inking member in engagement with the ink transferring member, the cam being designed to alternately perform the function mentioned.

Additional objects and advantages will become apparent from a consideration of the description following taken in connection with the accompanying drawings illustrating an operative embodiment.

In said drawings:—

Figure 1 is a plan view, partly broken away, of the improved device,

Figure 2 is a side elevation of such device,

Figure 3 is a plan view of the device showing the ink transferring sheet in retracted position,

Figure 4 is a longitudinal sectional view taken on the line 4—4 of Figure 3, showing the ink transferring sheet in position for making an impression,

Figure 5 is a longitudinal sectional view taken on the line 5—5 of Figure 1,

Figure 6 is a cross sectional view taken on the line 6—6 of Figure 5, and

Figure 7 is a cross sectional view taken on the line 7—7 of Figure 4.

Referring specifically to the drawings, 10 generally designates a suitable receptacle,

which is relatively shallow and open at the top for reception of the foot.

Located in the receptacle with their longitudinal edges disposed in grooves 11 in side walls 12 of the receptacle 10, are coacting plates 13 and 14, the former being slidable by reason of its mounting in the aforesaid grooves 11 and also being slidable through a slot 15 in one end wall 16 of the receptacle 10. Such plate 14 may have a finger opening 17 to facilitate its manipulation.

The separation of the plates 13 and 14 provides an opening or space 18 between them to accommodate an arch-engaging member 19 which is preferably of flexible metal and normally flat as in Figure 5 but capable of being bowed as in Figure 4, in order to fit the arch. Such member 19 has downturned flanges 20 and the same is supported on transverse rods or bolts 21 fastened in the side walls 12 of the receptacle. The adjustment of the plate 14 is relative to a scale 22.

The flexing of the element 19 is effected through the rocking of a transversely arranged cam 23 journaled by means of trunnions 24 and 25 in the walls 12, the latter trunnion having a crank or handle 26 fixed thereto for operation to move the cam 23. The handle 26 travels relatively to or across a detent plate 27 carried by one of the side members 12. At the free end of the handle 26, a screw 28 is detachably threaded as at 29 and the threaded element is extended to form a pin 30 to selectively engage holes 31 in the plate 27 according to the position in which the cam 23 is to be held, depending upon the curvature of the arch of the shoe into which the metatarsal arch is to be built.

When an impression is made, a sheet of paper is placed across the plates 13, 14 and 19 and an ink transferring sheet 32 is adapted to be arranged over the paper sheet. The sheet 32, at the under surface, as viewed in Figure 4, is adapted to carry ink thereon and hence when the foot engages the sheet 32 and presses the same against the paper, in combination with the curvature of the plate 19, an impression will be made on the paper sheet to show the various points of the foot and therefore form a basis for the application of

metatarsal pads or the other uses to which the invention may be put.

The sheet 32 is guided over rollers 33 fastened in the side members 12 and being attached by means of cables or flexible elements 34 to a roller or drum 35 having trunnions 36 journaled in the side walls 12 of the receptacle 10. The roller 35 is a conventional spring-return roller, urged to rotate so as to normally bind the cables 34 thereon as shown in Figures 1 and 5.

The free end of the sheet 32 is attached to a cross arm 37 of a bail 38 whose terminals are journaled as at 39 in brackets 40 fastened to the side members 12. The spring roller 35 due to its torsional action normally maintains the bail 38 in the position shown in Figures 1 and 5. The bail may, however, be swung one hundred and eighty degrees to the position shown in Figure 4 where the tension of roller 35 is overcome and the bail will remain in such position until returned to the position of Figure 5. It will be noted as in Figure 5, the sheet 32 does not extend across the plates 13 and 14 while in Figure 4 it does.

An inking pad is shown at 42 and while it may be of any approved construction, has an absorbent ink receiving and applying body 45 carried by a rigid back member 46. Fastened to the back member 46 is a blade spring 43, as best shown in Figure 6, whose terminals are entered in slots 44 of the side members 12. Such spring 43 normally tends to straighten and thereby urge the inking pad 42 to an elevated position as in Figure 4, or out of contact with the sheet 32. Normally cam 23 is in the position shown in Figure 5 where it engages the back 46 and accordingly depresses the inking pad 42 so that its surface 45 engages the ink receiving surface of the sheet 32, thus continually inking such sheet and preventing the drying of ink therefrom. The pad 42 may be inked from time to time or any means provided to accomplish the inking thereof.

47 designates a bracket that is removably mounted on an end of the receptacle 10, between studs 48, and is used when it is desired to determine the size of shoe to be worn by a customer, a conventional measuring scale (not shown) being laid on the plates 13 and 14 for this purpose, the heel of the foot engaging the bracket when the device is so used.

Particular attention is called to the fact that the cam 23 performs the dual function of lowering the inking pad and maintaining it normally in contact with the sheet 32 and releases such pad and bows the element 19 to form the same contour as the arch of the shoe into which the metatarsal pad is to be built.

The invention operates generally in the manner disclosed in my aforesaid Patent No.

1,684,339. Normally the cam 23 maintains the pad 41 lowered and in inking engagement with the sheet 32. When the location of the point of contact between some part of the foot and the in-sole of the shoe is desired, handle 26 is operated so as to move the cam 23 away from the pad so that the latter will elevate under the action of the blade spring 43. At the same time, the plate 15 is moved away from the plate 13 and further operation of the cam 23 elevates or bows the member 19 which may be accomplished prior or after a sheet of paper is disposed over the plates 13, 14 and 19 and the foot is engaged with the sheet 32, moves to the position of Figure 4 by throwing the bail 38 from the position shown in Figure 5, one hundred and eighty degrees to that shown in Figure 4.

Various changes may be resorted to provided they fall within the spirit and scope of the invention.

I claim as my invention:

1. A device of the character set forth including a plate upon which the foot is adapted to be placed and embodying sections adjustable relatively to provide an opening therebetween in registration with the arch of the foot, a flexible plate below the first plate, a receptacle in which the plates are mounted, means positioning the second plate above the base of the receptacle, means for bowing the flexible plate upwardly through said opening, and an inking member normally disposed in the receptacle below said plate and means mounting said inking member for movement to a position above and across said plates.

2. A device of the character set forth including a plate upon which the foot is adapted to be placed and embodying sections adjustable relatively to provide an opening therebetween in registration with the arch of the foot, a flexible plate below the first plate, a receptacle in which the plates are mounted, means positioning the second plate above the base of the receptacle, means for bowing the flexible plate upwardly through said opening, an inking member normally disposed in the receptacle below said plate and means mounting said inking member for movement to a position above and across said plates, and an inking pad operable by said bowing means and located between the flexible plate and said inking member in its first mentioned position.

3. A device of the character set forth including a plate upon which the foot is adapted to be placed and embodying sections adjustable relatively to provide an opening therebetween in registration with the arch of the foot, a flexible plate below the first plate, a receptacle in which the plates are mounted, means positioning the second plate above the base of the receptacle, means for bowing the flexible plate upwardly through said open-

ing, an inking member normally disposed in the receptacle below said plate and means mounting said inking member for movement to a position above and across said plates, an 5 inking pad operable by said bowing means and located between the flexible plate and said inking member in its first mentioned position, and means normally urging the inking pad out of engagement with the sheet.

10 4. A device of the class described comprising a receptacle, relatively movable plates therein, a plate associated with the first mentioned plates, a cam to bow the last mentioned plate between the first mentioned 15 plates for engagement with the arch of the foot, an inking sheet associated with said plates, inking means for said sheet, and means mounting said inking means for engagement by the cam and movement by the 20 latter into engagement with the sheet.

5. A device of the class described comprising a receptacle, relatively movable plates therein, a plate associated with the first mentioned plates, a cam to bow the last mentioned plate between the first mentioned plates for engagement with the arch of the foot, an inking sheet associated with said plates, inking means for said sheet comprising a pad, means mounting said inking means 25 for engagement by said cam and movement by the latter into engagement with the sheet, and means normally urging movement of the 30 pad away from the sheet.

6. A device of the class described comprising a receptacle, a roller therein, an inking sheet controlled by said roller, an inking pad engageable with said sheet, relatively movable plates for engagement by a foot, a cam engageable with the pad and operable to 40 move it into inking relation with said sheet, means mounting said sheet for movement across and above said plates, and said cam being operable against one of said plates to bow the same into engagement with a human 45 foot for measurement.

7. A device of the class described comprising a receptacle, a roller therein, an inking sheet controlled by said roller, an inking pad engageable with said sheet, relatively movable plates for engagement by a foot, a cam engageable with the pad and operable to move 50 it into inking relation with said sheet, means mounting said sheet for movement across and above said plates, said cam being operable against one of said plates to bow the same 55 into engagement with a human foot for measurement of the last mentioned plate having downturned flanges, cross members on which the last mentioned plate is positioned, and a 60 spring to urge movement of the inking pad away from said sheet.

In testimony whereof I affix my signature.
JOSEPH L. BARTH.
